TOY TRAIN

Robert G. Johnson, 22109 110th Ave. W., Edmonds, Wash., and Truxton Bee Troxell, 108 N. 155th St., Seattle, Wash.

Filed Aug. 1, 1961, Ser. No. 66,153

Term of patent 14 years

(Cl. D34—15)

FIGURE 1 is a side elevational view of the toy train, showing our new design;

FIGURE 2 is a front elevational view of the engine component thereof;

FIGURE 3 is a rear elevational view of the toy train;

FIGURE 4 is a rear elevational view of the engine component thereof;

FIGURE 5 is an exploded top perspective view of the toy train with the broken lines omitted from the engine portion for convenience of illustration.

The dominant features of our design reside in the full-line portions of the drawing.

We claim:

The ornamental design for a toy train, substantially as shown and described.
